CLAIM

We claim the ornamental design for a slide entryway, as shown and described.

DESCRIPTION

FIG. 1 is a front perspective view, taken from the left side, of a slide entryway embodying the present invention.

FIG. 2 is a front view of the slide entryway.

FIG. 3 is a rear view of the slide entryway.

FIG. 4 is a right-side view of the slide entryway.

FIG. 5 is a left-side view of the slide entryway.

FIG. 6 is a top view of the slide entryway; and,

FIG. 7 is a bottom view of the slide entryway.

The portions of the slide entryway shown in broken lines are for illustrative purposes only and form no part of the claimed design.
